UNITED STATES PATENT OFFICE.

PEDER MIKKELSEN, OF STAMFORD, CONNECTICUT, ASSIGNOR TO THE YALE & TOWNE MANUFACTURING COMPANY, OF STAMFORD, CONNECTICUT.

DOOR CHECK AND CLOSER.

1,259,428.

Specification of Letters Patent. Patented Mar. 12, 1918.

Application filed July 15, 1916. Serial No. 109,470.

To all whom it may concern:

Be it known that I, PEDER MIKKELSEN, a citizen of the United States, and a resident of Stamford, in the county of Fairfield and 5 State of Connecticut, have invented certain new and useful Improvements in Door Checks and Closers; and I do hereby declare the following to be a full, clear, and exact description of the invention, such as 10 will enable others skilled in the art to which it appertains to make and use the same.

My invention relates to improvements in door checks and closers of the type where the checking member, as for instance a piston 15 and its surrounding cylinder, is placed within and secured to a casing. It may be that the checking member acts by having the piston pulled away from the cylinder through a proper connection when the door 20 is opened, or the cylinder may be pulled away from the piston, the spring in either case operating to return the member which is pulled away to its closed position, subject to the checking action of a fluid which 25 is forced through a regulating valve opening.

The object of my invention is to provide automatic attachment of the checking member so that when it is operated through the 30 opening of the door or by the spring on its return, the checking member and its moving parts will automatically be in alinement thus facilitating the action of the check and reducing friction.

With these objects in view my invention 35 consists in the parts and combination of parts and in the details of construction as will be more fully explained and pointed out in the claims.

In the accompanying drawings, Figure 1 40 is a top view, partly in section and partly broken away, of a double acting check and closer embodying my invention; Fig. 2 is a view partly in plan and partly in section 45 of the piston and end of casing to which the piston is secured; Fig. 3 is a view in vertical section partly in elevation of the parts shown in Fig. 2; Fig. 4 is a view in section on the line $x-x$ of Fig. 3, the projection

on the piston being in elevation; Figs. 5, 6 50 and 7 are views of the piston, and Figs. 8, 9 and 10 are views of modifications.

8 represents a casing to be embedded in the floor below the door, and closed at its upper side by cover plates 9 and 10 secured 55 by screws to laterally projecting flanges at the upper open edge of the casing.

Mounted in the casing and cover section 10, adjacent one end of the casing, is the vertical spindle or shaft 11, the lower end of 60 which is seated in a socket 12 in the bottom of the casing and is supported near its upper end by a suitable bearing formed in or carried by the section 10 of the cover. The upper end of the spindle 11, which projects 65 above the cover is made angular in cross section and is adapted to enter a correspondingly formed recess in a shoe to be carried by the lower edge of the door.

The spindle or shaft 11 is provided with 70 a cam, preferably of heart shape as shown in dotted lines in Fig. 1, and adapted to engage rollers carried by the yoke 13, which is connected with the rod 14 carrying the cylinder 15.

The cylinder is provided at its outer open end with a peripheral flange 15^a which is engaged by one end of the spring 16, the opposite end of said spring bearing against the stop plate 17 through which the rod 14 80 passes, the said stop plate being restrained by its contact with the casing and cover section 10, against movement toward the shaft 11, hence when the shaft is turned as in opening the door, the spring 16 will be 85 compressed or put under tension and operate to close the door when the latter is released.

The cylinder 15 is mounted and reciprocates on the hollow piston 18, and is provided at its closed end with an inlet port 15^b for the passage of the checking liquid to the interior of the cylinder and piston; this port being closed during the closing movement of the door by a ball valve 15^c, so 95 that the liquid must, at such time escape through the port 15^d.

The hollow piston 18 is provided at its

rear closed end with a rearwardly extending lug, the latter being preferably integral with the piston. The axis of this lug is vertical and the lug has a curved periphery 5 the central part 18^a of which is in the arc of a circle, while the parts thereof 18^b above and below the central portion are made tapering so that the central part of the lug constitutes the main bearing. The arc of 10 the lug, is as shown, considerably greater than a half circle, and it rests within a recessed seat 19 formed in the outer end of the casing 8, the said seat 19 being open at the top and having a restricted opening at the 15 front. This recessed seat is circular in cross section and of a diameter to readily receive the lug, and permit the latter to turn freely therein when seated, but which embraces the lug more than half way around so as to absolutely prevent any movement of the latter 20 in the direction of the length of the casing. The lug is so shaped that its main bearing is on or near its center, so that it can lift or pivot slightly in a vertical direction, and 25 can of course turn to a limited extent around the axis of the lug, and forms in effect a universal joint. This provides for proper coördination of the piston with its cylinder during the movements of the latter, and 30 avoids the necessity of special care and alinement of parts in assembling, or any loss of friction in the event the alinement is not perfect. In other words it alines itself with the cylinder as the latter slides back 35 and forth on it.

To prevent the lug from rising out of its seat, a projection 20 is formed integral with the section 9 of the cover plate, which projection, when the parts are assembled, comes 40 within such distance of the top of the lug as shown, or if preferred, the top of the end of the piston, as to prevent any undue vertical movement.

The advantage of this construction is that 45 the alinement of the parts is automatic, and therefore avoids the labor necessary to making alinement accurate, and does away with all screws and other fastenings to hold the parts in place.

50 I have shown and described the piston having the lug or trunnion engaging means connecting it with the casing, but it is clearly evident that the cylinder may be so connected, hence I would have it understood 55 that my invention comprehends the connection of either checking member with the casing.

Again, instead of forming the lug integral with the checking member as previously 60 explained, it may be integral with the casing and the checking member be provided with a block 19^b having the recessed seat as shown in Fig. 8, in which event the

escape valve 19^a would be in the block 19^b, at one side of the seat, instead of in the lug, 65 where it is located when the lug is integral with the checking member.

In the construction illustrated in Figs. 9 and 10, I have shown a trunnion 21 fitted at its ends in recessed seats in the projections 22 formed respectively on the bottom or end of the casing 8 and the cover plate 9. This trunnion 21 carries a ball 23, which may or may not be integral with or fixed to the trunnion. The checking member 18 70 is provided with an end projection 24 having a semi-spherical seat for the ball, and a plate 25 having a similarly shaped seat is secured to the projection 24 by screws or otherwise, the two parts forming a spherical 80 seat for the ball, so that the whole forms a universal joint and permits the checking member 18 to move in any direction. In this latter form the trunnion 21 also has an endwise movement as well as a rotary move- 85 ment.

It is also evident that many slight changes might be resorted to in the relative arrangement of parts shown and described without departing from the spirit and scope of my 90 invention. Hence I would have it understood that I do not wish to confine myself to the exact construction and arrangement of parts shown and described, but

Having fully described my invention what 95 I claim as new and desire to secure by Letters-Patent, is:—

1. In a door check and closer, the combination of a casing, a checking member within the casing adapted to be secured 100 against movement, one of said parts provided at one end with an integral recessed seat and the other part provided at its end adjacent said seat with an integral trunnion or journal to enter the seat, whereby said 105 checking member may oscillate in the casing, the checking member having a port terminating adjacent the axis on which said checking member turns, and a door spindle mounted in the casing and connected with 110 said checking member.

2. In a door check and closer, the combination of a casing, a checking member within the casing, one of said parts having an integral recessed seat and the other part 115 a corresponding journal or bearing to enter said seat, the said journal or bearing and its seat constructed to permit of a limited universal movement of the checking member, and a door spindle mounted in the casing and connected with said checking member. 120

3. In a door check and closer, the combination of a casing and a checking member, one of said parts having an integral re- 125cessed cylindrical seat, the latter being open

at its top and having a restricted opening at its front, and the other part having a cylindrical lug at one end to rest within said recessed seat and a cover plate having a projection adapted to prevent the vertical displacement of said parts.

5 In testimony whereof, I have signed this

specification in the presence of two subscribing witnesses.

PEDER MIKKELSEN.
